CLAIM

The ornamental design for a masticating juicer attachment, as shown and described.

DESCRIPTION

FIG. 1 is a top-front-right perspective view of a masticating juicer attachment showing my design;

FIG. 2 is a bottom-front-right perspective view thereof;

FIG. 3 is a bottom-left-back perspective view thereof;

FIG. 4 is a front view thereof;

FIG. 5 is a back view thereof;

FIG. 6 is a left-side view thereof;

FIG. 7 is a right-side view thereof;

FIG. 8 is a top view thereof;

FIG. 9 is a bottom view thereof; and,

FIG. 10 is another top-front-right perspective view thereof.

The broken lines in FIGS. 1, 2, 6, 8, and 9 depict portions of the masticating juicer attachment that form no part of the claimed design.

The broken lines in FIG. 10 depict environmental structure in the form of a juicer that form no part of the claimed design.

1 Claim, 10 Drawing Sheets
